UNITED STATES PATENT OFFICE.

LEE J. COTTON, OF DE QUINCY, LOUISIANA.

SAFETY SWITCH LEVER AND LOCK.

1,375,035.

Specification of Letters Patent. Patented Apr. 19, 1921.

Application filed December 3, 1920. Serial No. 428,124.

To all whom it may concern:

Be it known that I, LEE J. COTTON, a citizen of the United States, residing at De Quincy, in the parish of Calcasieu and State 5 of Louisiana, have invented certain new and useful Improvements in Safety Switch Levers and Locks, of which the following is a specification.

This invention relates to new and useful 10 improvements in a safety switch lever and lock.

One object of the invention is to provide in combination with a switch stand specially adapted for use in connection with rail- 15 ways of a lever for manipulating the switch so as to readily open or close the same and to automatically lock the switch in either position.

Another object is to provide a safety pin, 20 in combination with said lock, whereby the lock may be held in inactive position.

With the above and other objects in view the invention has particular relation to certain novel features of construction, opera- 25 tion and arrangement of parts, an example of which is given in this specification and illustrated in the accompanying drawings, wherein:—

Figure 1 is a plan view of the device 30 shown in operative connection with the switch.

Fig. 2 shows a side view thereof.

Fig. 3 shows an enlarged fragmentary side view partially in section.

Fig. 4 shows an enlarged fragmentary plan view.

Fig. 5 shows a fragmentary view of the lever showing the lock therein.

Fig. 6 shows a transverse sectional view 40 thereof, and

Fig. 7 shows an enlarged fragmentary rear view of the lever.

Referring now more particularly to the drawings wherein like numerals of reference 45 designate similar parts in each of the figures, the numerals 1 and 2 designate the rails of the main line track, the latter of which is formed into a movable switch in the usual way, and the numerals 3 and 4 designate the rails of the switch track. Some 50 of the railway ties as 5 are extended to form a suitable support for the stand, and secured to the extended ends of these ties there is a base plate 6 of the usual construc- 55 tion. Upstanding from this plate are the

legs 7 mounted upon the upper end of which is the circular table 8 which is provided with deep marginal notches 9, spaced a suitable distance apart. The table 8 has a central bearing through which the vertical 60 shaft 10 extends. The lower end of this shaft works in a bearing 11 which is carried by a cross brace 12 whose respective ends are fastened to the legs 7. The lower end of the shaft 10 has a short arm 13 extending out at right angles thereto and one end of the link 14 is pivoted to the free end of this arm. The corresponding ends of the rails 2 and 3 are movable back and forth 65 across the ties in the well known manner, 70 and they are connected by a cross bar 15, and the other end of the link 14 is attached to this cross bar. Fastened to the shaft 10, above the table 8, there is a throw arm 16, 75 by means of which said shaft may be turned. The outer end of this throw arm is bifurcated, as shown in Fig. 4, and pivoted between the fingers thereof there is the lever 17. This lever normally depends in vertical 80 position and rests in one of the notches 9, 80 and within it there is a spring lock which has the usual bolt 18 adapted to engage in a suitable recess 19 in the side of the notch 9 to lock the lever 17 and the arm 16 against movement and thereby to lock the switch in 85 the desired position. The bolt 18 is seated against the coil spring 20 which normally holds it projected from the lock and said projecting end is beveled to cause it to engage in the recess 21, and upstanding from 90 said bolt are the pins 22 and 23. In alignment between these pins there is a key hole 24, provided to receive the key 25, which when inserted and turned will operate against the pin 22 to release the bolt 18. 95 When unlocked, the lever 17 may be raised into horizontal position and the arm 16 then moved so as to rotate the shaft 10 and open or close the switch. When the switch is thrown, the lever 17 may then be dropped 100 into the corresponding notch 9 and it will be automatically locked therein by the bolt 18. The outward movement of the bolt is limited by the cross pin 26 forming a stop against which the pin 23 engages. 105

During switching operations, it is often necessary to throw the switch several times before locking it and for this purpose I have provided a safety attachment which will hold the bolt 18 withdrawn while operating 110

the switch. This device includes the hollow plug 27 which is screwed into the lever 17 opposite the bolt 18. This plug has a central bearing through which the safety pin 28 slides and within the plug 27 there is a coil spring 29 which is attached to said safety pin and normally presses its inner end against the bolt 18. The adjacent side of this bolt has a recess 30 and when the bolt 10 is withdrawn, by the key 25, into unlocking position the safety pin engages in said recess and holds said bolt in said position and permits the switchman to throw the switch back and forth until the present switching 15 operations are completed and it is desired to again lock the switch. During these operations the key is locked against detachment from the lock by the pin 23 which holds it against turning. The outer end of the pin 28 has an enlarged head 31 with depending lugs 32 which work in slots 33 in the outer end of the plug 27. When it is desired to release the safety pin to permit the bolt 18 to operate, this is done by withdrawing 20 said pin, to release the lugs 32 and giving it a quarter turn. The lugs 32 will then engage against the outer end of the plug 27, and in the notches 34 thereof, and said pin will be thereby held in released position and 25 will permit the bolt 18 to operate.

When the lever is in locked position the safety attachment fits into a socket 35 in the table 8 and is thereby inclosed and protected against interference.

35 A switch lock of the character described is much simpler than those now in common use and may be very easily operated. When the switch is thrown either into open or closed position it will be automatically locked in said position and there held until again positively thrown so that there will be no danger of the switch being inadvertently left in the wrong position.

It is to be further noted that the lever 17 40 is detachable, and consequently can be easily applied to any form of switch stand now in common use.

What I claim is:—

1. A device of the character described, including the combination with a railway switch of a switch stand fixed relative to the railway track, a table fixed to said stand and provided with marginal notches, a vertical shaft having a bearing in said table, a lateral arm carried by said shaft, a link pivoted at one end to the free end of said arm and at its other end to said switch, a throw arm fixed to said shaft adjacent the table, a lever pivoted to the outer end of said throw arm and adapted to normally rest in either of said notches, a spring lock carried by said lever and provided with means to automatically lock the same in said notch, said lock including a bolt having a recess therein, a safety pin adapted to engage in the recess and a yieldable cushion whereon the pin is mounted, said pin constituting means for preventing the operation of the lock, when seated in said recess. 60

2. A device of the character described, including the combination with a railway switch of a stand fixed relative to the railway track, a table fixed to the stand and provided with marginal notches and having recesses forming extensions of said notches, 75 a vertical shaft having a bearing in the table, said shaft being operatively connected to the switch, a throw arm fixed to said shaft adjacent the table, a lever pivoted to the outer end of the arm and adapted to rest in either of the notches, a lock carried by said lever and provided with means to automatically lock the same in said notch, and means for preventing the operation of the lock, 80 said last means being inclosed by said lever in the corresponding recess when the lever is in locked position. 85

In testimony whereof I have signed my name to this specification in the presence of two subscribing witnesses.

LEE J. COTTON.
